UNITED STATES PATENT OFFICE.

MORITZ MEYER, OF NEW YORK, N. Y.

AUXILIARY BOX-COVER.

SPECIFICATION forming part of Letters Patent No. 671,833, dated April 9, 1901.

Application filed February 2, 1901. Serial No. 45,717. (No model.)

To all whom it may concern:

Be it known that I, MORITZ MEYER, a citizen of the United States, and a resident of the city of New York, borough of Manhattan, in 5 the county and State of New York, have invented a new and Improved Auxiliary Box-Cover, of which the following is a full, clear, and exact description.

The object of the invention is to provide a 10 new and improved auxiliary box-cover more especially designed for use on cigar-boxes and the like and arranged for convenient attachment to a box without disturbing the contents thereof or without requiring removal of 15 the original box-cover, the improvement allowing convenient viewing of the contents of the box, protecting the contents from dust, moisture, &c., and permitting opening and closing of the box to obtain access to the contents thereof whenever desired.

The invention consists of novel features and parts and combinations of the same, as will be fully described hereinafter and then pointed out in the claim.

25 A practical embodiment of the invention is represented in the accompanying drawings, forming a part of this specification, in which similar characters of reference indicate corresponding parts in all the views.

30 Figure 1 is a perspective view of the improvement as applied and with both covers in an open position. Fig. 2 is a transverse section of the same with the original box-cover open and the auxiliary box-cover closed. 35 Fig. 3 is a rear elevation of the same with part of the original box-cover broken out, and Fig. 4 is an enlarged rear perspective view of the improvement.

The cigar-box on which the improvement 40 is shown applied is provided with the usual body A, a cover B, connected to the back of the box by a suitable hinge C, and an auxiliary cover for closing the box and permitting of viewing the contents thereof, consisting, 45 essentially, of a frame D, made of sheet metal or other suitable material and containing a panel D' of transparent or translucent material, such as glass, celluloid, or the like. The frame D is provided on its ends and on the

front with depending flanges D² for fitting 50 over the outside of the ends of the box-body A and the front thereof, as will be readily understood by reference to Figs. 2 and 4. The rear end of the frame D is formed into an eye D³, engaged by a pintle D⁴, terminating at its ends in angular arms D⁵, formed with eyes D⁶, engaged by nails E, driven into the box-body A at the back thereof, below the hinge C and at the side of the ends of the cover B, so that the latter can be readily 55 swung into an open position, and then the auxiliary cover is free to swing into an open or closed position without the least interference with the original box-cover B. The eye D³ and the pintle D⁴, with its arms, form a 60 hinge for swinging the auxiliary box-cover into an open or closed position.

It is understood that the ends of the body A of a cigar-box extend somewhat above the back and the front of the box-body, and the 70 cover B snugly rests on said back and said front when closed. The eye D³ extends on the top of the back of the box-body and terminates a distance from the ends of the box-body, as is plainly indicated in Fig. 1, to permit of extending the pintle D⁴ to the ends of 75 the box-body and to then have the arms D⁵ extend upward outside of the ends of the cover B. Thus the auxiliary cover can be readily swung shut or open at the time the 80 cover B is open to permit convenient access to the contents of the box.

By having a transparent or translucent panel the contents of the box can be readily seen at any time, and by ordinarily keeping 85 the box closed by the auxiliary cover dust, moisture, &c., are prevented from passing to the contents of the box. By having the flanges D² on the auxiliary box-cover the box is rendered completely dust-proof. 90

Having thus fully described my invention, I claim as new and desire to secure by Letters Patent—

An auxiliary box-cover, comprising a frame, a transparent or translucent panel in the 95 frame, a hinge for connecting the frame with the box, the hinge having its eye member formed integral on the back of said frame,

the pintle of the hinge being formed with angular arms having eyes, and nails driven through said arm-eyes, to secure the angular arms to the box below the hinge of the original box-cover and beyond the ends thereof, as set forth.

In testimony whereof I have signed my

name to this specification in the presence of two subscribing witnesses.

MORITZ MEYER.
